234,191

FLAG OR SIMILAR ARTICLE

Jack Might and Arnold O. Madrid, Colorado Springs, Colo.; said Madrid assignor of a fractional part interest to said Might

Filed Aug. 2, 1973, Ser. No. 385,110

Term of patent 14 years

Int. Cl. D29—02

U.S. Cl. D10—109

FIG. 1 is a perspective view of a flag or similar article showing our new design, the bicycle being shown in broken lines for illustrative purposes only.

FIG. 2 is an enlarged side elevational view thereof.

FIG. 3 is an enlarged front elevational view thereof.

We claim:

The ornamental design for a flag or similar article, as shown and described.
